UNITED STATES PATENT OFFICE.

ANDREW H. CANDEE, OF PITTSBURGH, AND LLOYD J. HIBBARD, OF WILKINSBURG, PENNSYLVANIA, ASSIGNORS TO WESTINGHOUSE ELECTRIC AND MANUFACTURING COMPANY, A CORPORATION OF PENNSYLVANIA.

RELAY.

Application filed August 7, 1917. Serial No. 184,804.

To all whom it may concern:

Be it known that we, ANDREW H. CANDEE, a citizen of the United States, and a resident of Pittsburgh, in the county of Allegheny and State of Pennsylvania, and LLOYD J. HIBBARD, a citizen of the United States, and a resident of Wilkinsburg, in the county of Allegheny and State of Pennsylvania, have invented a new and useful Improvement in Relays, of which the following is a specification.

Our invention relates to relays and particularly to protective devices and systems for electric railway vehicles.

One object of our invention is to provide means that shall be adapted to automatically control the energization of an electro-responsive device to preclude its operation under predetermined conditions and to insure its operation under other predetermined conditions.

Another object of our invention is to provide a relay of the above-indicated character that shall be adapted to effect disengagement of one pair of contact members when it is operated and engagement of another pair of contact members only when it is returned to its initial position after being operated.

A further object of our invention is to provide a relay for a system of the above-indicated character that shall be inexpensive to construct and effective in its operation.

In practicing our invention, we provide a pantograph lowering electromagnet, a switch for manually controlling the circuit of the same and a relay that is adapted to automatically open the circuit of the magnet when an overload obtains upon the system, to preclude the pantograph from being lowered under these conditions and to provide an independent circuit for the electromagnet after the overload is removed to insure the lowering of the pantograph, irrespective of the position of the switch.

Figure 1 of the accompanying drawing is a diagrammatic view of a pantograph-lowering device for an electric vehicle embodying our invention; Fig. 2 is a fragmentary view of the device shown in Fig. 1, illustrating one of its operative positions, and

Fig. 3 is a view taken along the line III—III of Fig. 1.

A pantograph 1 is operatively connected to a trolley conductor 2 and is adapted to supply energy to the primary winding 3 of a transformer 4, the secondary winding 5 of which is adapted to be connected to the motors (not shown) of an electric vehicle. An electromagnet 6 is adapted to lower the pantograph 1 and is provided with a manually operated switch 7 and with a relay 8 for controlling the circuit thereof.

The relay 8 is mounted on a panel board 9 and comprises a frame 10 having a magnetizable core portion 11 around which is disposed a winding 12. A rod 13 extends through an opening 14 in the core portion 11 and has two bridging contact members 15 and 16 mounted thereon. An armature 17 is pivotally mounted on a pin 18 on the frame 10 and is adapted to engage the lower end 19 of the rod 13 when it is attracted by reason of the proper energization of the winding 12. The rod 13 is guided by a projection 20 on the frame 10, and springs 21 and 22 are provided for returning the rod 13 to its initial position under predetermined conditions. A scale plate 23 is provided for cooperation with a pointer 24, at one end of the armature 17, to indicate the current setting of the relay, and an adjusting screw 25 is provided for adjusting the initial position of the armature 17.

The bridging contact member 15 is adapted to normally engage two stationary contact members 26 and 27, and the bridging contact member 16 is adapted to normally engage the arms 28 and 29 of contact devices 30 and 31. The contact device 30 comprises the arm 28 and an arm 32 which are pivotally mounted on a pin 33. The arm 28 is provided with an insulating member 34 that normally engages the bridging contact member 16. A spring 35 is adapted to normally retain the insulating piece 34 in engagement with the bridging contact member 16, and a latch 36 is provided to engage the arm 32 when the contact device 30 is raised by reason of the movement of the rod 13. The contact device 31 comprises the arm 29, upon which is mounted an insulating member 37, and an

arm 38 which are pivotally mounted on a pin 39. A spring 40 is adapted to hold the insulating piece 37 in engagement with the bridging contact member 16, and a latch 5 41 is provided to engage the arm 38 when the contact device 31 is moved upwardly by reason of the operation of the rod 13.

The winding 12 is operatively connected to the secondary winding 42 of a series 10 transformer 43 the primary winding 44 of which is connected in series with the primary winding 3 of the main transformer 4. One terminal of the winding of the electro- 15 magnet 6 is connected to the stationary contact member 26 and to the contact device 30. The other terminal of the winding of the electromagnet 6 is connected to one terminal of the source 45 of electromotive force, the other terminal of which is connected to the 20 adjusting screw 25 and to one terminal of the switch 7. The other terminal of the switch 7 is connected to the stationary contact member 27. The adjusting screw 25 is insulated from the frame 10 which is electrically connected to the contact device 31.

Under normal conditions in the vehicle being protected, if it is desired to lower the pantograph 1, the switch 7 is closed and the circuit is completed from the source 45 of 30 electromotive force through the switch 7, contact members 26, 27 and 15 and the winding of the electro-magnet 6. When an overload or short circuit obtains on the vehicle, it is not advisable to lower the pantograph 35 because it will be required to constitute an interrupter of relatively large currents when it is disengaged from the trolley conductor. However, if an overload or a short circuit obtains on the vehicle, the winding 12 will 40 be sufficiently energized to cause the armature 17 to move upwardly, and such movement will effect disengagement of the bridging contact member 15 and the stationary contact members 26 and 27, thereby opening 45 the circuit through the winding of the electromagnet 6. The upward movement of the rod 13 causes the bridging contact member 16 to turn the contact devices 30 and 31 about the pins 33 and 39 until the arms 32 50 and 38 thereof are latched in their upper positions by the latches 36 and 41, respectively.

If the overload is removed from the circuit, the armature 17 will drop into engagement with the adjusting screw 25, and the bridging contact member 16 will drop into engagement with the arms 32 and 38 of the contact devices 30 and 31, respectively. This will cause a circuit to be completed 60 from one terminal of the source 45 of electromotive force through the adjusting screw 25, armature 17, frame 10, arm 38 of the contact device 31, bridging contact member 16, arm 33 of the contact device 30 and the 65 winding of the electromagnet 6 to the other

terminal of the source 45 of electromotive force. Thus, a closed circuit will be established in shunt to the switch 7 and contact members 26, 15 and 23 to thereby effect lowering of the pantograph 1, irrespective 70 of the position in which the switch 7 is, under these conditions.

In order to reset the relay 8, the latches 36 and 41 may be depressed to permit the springs 35 and 40 to return the contact devices 30 and 31 to their initial positions and the springs 21 and 22 to move the bridging contact member 15 into engagement with the stationary contact members 26 and 27.

We do not limit our invention to the particular form of relay shown, as various modifications may be made therein without departing from the spirit and scope of the invention as set forth in the appended claims.

We claim as our invention:

1. A relay comprising a movable member, two bridging contact members mounted thereon, co-operating contact members for the bridging members, means for actuating the movable member to disengage only one 90 bridging member from its co-operating contact members, and means for effecting the engagement of the other bridging member with its co-operating contact members when the movable member is released by the actuating means.

2. A relay comprising a movable member, two sets of contact members actuated thereby, means for actuating the movable member to effect disengagement of one set of 100 contact members, and means for effecting the engagement of the other set only when the movable member moves toward its initial position.

3. A relay comprising a movable member, 105 a normally engaged contact device, a normally disengaged contact device, means for actuating the movable member to disengage the normally engaged contact device and means for effecting the engagement of the 110 other contact device only when the movable member moves toward its initial position.

4. A relay comprising a movable member, a stationary contact member, a pivotally mounted contact member, two contact members mounted on the movable members for engaging the said stationary and pivotally mounted contact members, means for actuating the movable member to effect disengagement of one of the movable members 120 and the stationary contact member and to move the pivotally mounted contact member to another position, and means for maintaining the pivotally-mounted contact members in said position to engage the other movable contact member when the movable member moves towards its initial position.

5. A relay comprising a movable member, a pivotally mounted member having a contact portion thereon, a contact member 120

mounted on the movable member, means for actuating the movable member to cause the movable contact member to actuate the pivotally mounted member, and means for holding the pivotally mounted member to engage the movable contact member only when the movable member moves toward its initial position.

6. A relay comprising a movable contact member, a movable member having a contact portion thereon, means for so moving the movable contact member that it shall actuate the movable member having the contact portion thereon, and means for holding the said movable member having the contact portion thereon in its actuated position to effect engagement between the movable contact member and the contact portion when the movable contact member moves toward its initial position.

7. A relay comprising a movable contact member, a movable member having a contact portion thereon, means for so moving the movable contact member that it shall actuate the movable member having the contact portion thereon, and means for holding the said movable member having the contact portion thereon in its actuated position to effect engagement between the movable contact member and the contact portion only when the movable contact member moves toward its initial position.

8. A relay comprising a movable contact member, a second movable member having a contact portion thereon, means for so moving the movable contact member that it shall actuate the second movable member, and a latch for retaining the second movable member in its actuated position to effect engagement between its contact portion and the movable contact member only under predetermined conditions.

9. A relay comprising a movable contact member, a second movable member having a contact portion thereon, means for so moving the movable contact member that it shall

actuate the second movable member, and a latch for retaining the second movable member in its actuated position to effect engagement between its contact portion and the movable contact member only when said movable member moves toward its initial position.

10. In an electric circuit, the combination with an electro-responsive device, energizing means therefor and a switch for controlling the circuit thereof, of a relay energized from the circuit for rendering the switch ineffective when an overload obtains on the circuit and for automatically energizing the electro-responsive device when the overload is removed from the circuit.

11. In an electric circuit, the combination with an electromagnet, a control source of electromotive force and a switch for connecting the electromagnet in circuit with the control source of electromotive force, of a relay energized from the main circuit for opening the circuit through the switch when an overload obtains on the main circuit and for completing a second control circuit through the electromagnet and the source of electromotive force when the overload is removed from the main circuit.

12. In an electric circuit, the combination with an electromagnet, a control source of electromotive force and a switch for connecting the electromagnet in circuit with the control source of electromotive force, of a relay energized from the main circuit for opening the control circuit through the switch when an overload obtains on the main circuit and for completing an auxiliary control circuit in shunt relation to the switch when the overload is removed from the main circuit.

In testimony whereof, we have hereunto subscribed our names this 17th day of July, 1917.

ANDREW H. CANDEE.
LLOYD J. HIBBARD.
